UNITED STATES PATENT OFFICE.

WILLIAM H. GRAY, OF BROOKLYN, NEW YORK, ASSIGNOR TO THE GLEN COVE MACHINE COMPANY, (LIMITED,) OF SAME PLACE.

GEARING FOR WOOD-PLANER FEEDS.

SPECIFICATION forming part of Letters Patent No. 360,150, dated March 29, 1887.

Application filed December 8, 1886. Serial No. 220,955. (No model.)

To all whom it may concern:

Be it known that I, WILLIAM H. GRAY, of Brooklyn, (Green Point,) in the county of Kings and State of New York, have invented a new 5 and useful Improvement in Gearing for Wood-Planer Feeds, of which the following is a specification.

In wood-planing machines the one or more sets of feed-rolls are commonly driven by gearing from a shaft extending transversely of the machine, and which is usually known as the "pinion-shaft." In planing lumber of different degrees of hardness, and also in planing knotty and crooked lumber and straight and 15 clear lumber, it is necessary to drive the feed-rolls at different velocities; and to this end the means through which motion is transmitted to the pinion-shaft are commonly of such nature as to provide for imparting to said shaft 20 a variable speed from a driving or counter shaft which rotates at a uniform speed. The pinion-shaft is commonly driven from the counter-shaft or driving-shaft, which extends transversely of the machine at the front thereof, 25 and from which shaft also the side cutter-spindles and the upper and lower cutter-heads are driven.

In carrying out my invention I employ reversely-arranged friction-disks having a common 30 axis, and which are usually mounted upon or concentric with the counter or driving shaft at the front of the machine, and I also employ a transmitting-shaft extending lengthwise of the machine and transversely to 35 the pinion-shaft and geared with the pinion-shaft, and a friction-pinion, sliding upon the transmitting-shaft toward and from the center of said disks and receiving motion by frictional engagement with them.

In a system of mechanism where a friction-pinion receives motion from a friction-disk and is adapted to slide toward and from the center of the disk, and in which the shaft is pressed against the surface of the disk, there 40 is rapid wear of the parts and side strain. By means of the reversely-arranged disks, one of which is secured to the counter or driving shaft, while the other is free to slide axially and is loaded by a weight or otherwise to press it 45 toward the first disk, the disks are held in strong frictional engagement with the pinion

and without any side strain of the transmitting-shaft or other parts. In order to cause the free or sliding disk to rotate synchronously with the positively-driven disk upon the counter or driving shaft, and in a reverse direction thereto, I connect the two disks by bevel-gearing. It is sometimes desirable after a stick 55 or piece of lumber is partially planed to withdraw it from the machine, and to afford facility 60 for moving the feed-rolls backward as well as forward I connect the transmitting-shaft with the pinion-shaft by means of reversely-arranged pinions on the transmitting-shaft, which gear with a bevel-wheel on the end of the pinion-shaft, and which may, either of them, be 65 locked to the transmitting-shaft so as to impart power therefrom by means of a clutch sliding upon the transmitting-shaft.

The invention consists in novel combinations of parts, which are above referred to and hereinafter particularly described, and pointed out in the claims.

In the accompanying drawings, Figure 1 is a plan of such portions of a planing-machine 75 as are necessary to illustrate my invention. Fig. 2 is a side elevation and partial section upon the plane of the dotted line $\alpha\alpha$, Fig. 1; and Fig. 3 is a partial transverse section and end view upon about the plane of the dotted 80 line yy , Fig. 1.

Similar letters of reference designate corresponding parts in the several figures.

A designates the side frames of the machine, and B a pinion-shaft, which extends transversely of the machine, and from which the one or more pairs of feed-rolls are to be driven. A system of spur-gearing is commonly employed to connect the pinion-shaft B with the feed-rolls; but as such gearing is well-known 85 to mechanics familiar with wood-planing machines I have only shown a single wheel or pinion, b, upon the shaft B.

At the front end of the machine is the usual counter or driving shaft, C, which is provided with fast and loose pulleys $C^1 C^2$, for the reception of a driving-belt for operating the machine, and on which are pulleys C^3 , from which belts may drive to operate the upper and lower cutter-heads, and other pulleys, C^4 , 95 from which belts may drive to operate the side cutter-spindles at the opposite end of the ma- 100

chine. This shaft C, which I term the "driving" or "counter" shaft, is commonly employed in all or nearly all planing-machines, and is fitted to bearings *c* in the side frames, 5 A. The counter or driving shaft C has a uniform rotary motion imparted to it, while it is desirable that the pinion-shaft B should be driven from the counter-shaft through mechanism, which will provide for readily varying 10 the speed of said pinion-shaft B.

D D' designate two reversely-arranged friction-disks, which have parallel faces and a common axis concentric with the axis of the shaft C. In this example of my invention 15 the disk D, which may be termed the "master" disk, is secured fast to the shaft by a set-screw, *d*, as shown in Fig. 3, or by other suitable means, while the disk D' is free to turn and slide upon the sleeve *c'*, which may form 20 a continuation of the adjacent shaft-bearing *c*. Suitable means should be employed for pressing the disk D' in a direction toward the disk D, and, as here represented, the means consist of a lever, D², fulcrumed at *d'*, provided with 25 a weight, *d''*, which may be adjustable, and having its lower and shorter arm engaging a grooved collar or hub, *d'*, upon the disk D'.

In order to insure the synchronous rotation of the two disks D D' in reverse directions, I 30 have shown them as constructed on their inner faces, near the center, with circular series of bevel gear-teeth *d⁴*, with which engages a bevel-pinion, *d⁵*, upon the upright shaft D³. This shaft D³ at its lower end fits a bearing 35 formed in the sleeve or block *d''*, loosely mounted on the shaft C, and at its upper end is supported by a bearing, *d'*, attached to the frame. The master disk D, through the bevel gear-teeth *d⁴* and pinion *d⁵*, imparts positive 40 rotation to the other disk, D', in a reverse direction.

E designates a transmitting-shaft, which extends lengthwise of the machine and transversely to both the shafts B C. It is journaled 45 in bearings *e*, attached to the side frame, and at its end has a bearing in the sleeve or collar *d''*, which is supported by the shaft C, as best shown in Fig. 2.

Upon the transmitting-shaft E is fitted a 50 friction-pinion, E', which is free to slide lengthwise of the shaft in a direction toward and from the shaft C, and which lies between the two friction-disks D D'. This pinion may be composed of paper or leather disks 55 suitably clamped together, or may be otherwise constructed, so as to give it a surface for engaging frictionally with the disks D D'. The pinion E', although free to slide on the shaft E, is locked to turn therewith by suitable means, here shown as consisting of a feather or spline, *e'*, in the shaft. It will be obvious that as the pinion E' is slid toward the shaft C and the center of the disks D D' the speed of the transmitting-shaft E will be 60 decreased, while when said pinion is moved near to the periphery of the disks D D', as is

shown in Fig. 2 and also in Fig. 1, the speed of the shaft E will be increased.

The sliding pinion E' should have suitable mechanism connected with it for moving it upon the shaft E while the machine is in operation. As here represented, this shifting mechanism consists of a rock-shaft, *e²*, having a downwardly-extending arm, *e³*, which engages a groove in the pinion and with the upwardly-extending arm *e⁴*, to which is connected a handle-rod, *e⁵*. This handle-rod is provided with notches *e⁶*, which may, any one of them, engage a locking and supporting tooth or projection, *e⁷*. These means provide for 80 moving the pinion E' as may be desired, and also serve to hold it in position after adjustment. 75

The means here shown for gearing the transmitting-shaft E with the pinion-shaft B consists of a bevel-wheel, B', upon the end of the pinion-shaft, and bevel-pinions B², which are reversely arranged, so as to engage the wheel B' at diametrically-opposite points. The pinions B² are not secured to the shaft, but are 90 loose thereon, and either of them may be locked to the shaft, so as to transmit motion therefrom to the pinion-shaft B, by means of a sliding clutch, B³, which may be locked to turn with the shaft E by means of a spline or feather, *b'*, and groove in a well-known manner. When one pinion B² is locked to the shaft E, motion will be transmitted from the shaft E to the shaft B, and thence to the feed-rolls in a direction to feed the lumber forward 100 to the cutters, and when the clutch B³ is shifted so as to lock the reversely-arranged pinion B² to the shaft E motion will be transmitted to the shaft B, and thence to the feed-rolls in a reverse direction to the feeding movement of 105 said rolls, and the lumber will by the rolls be moved backward or thrown out of the machine. This provides for the ready withdrawal by power of lumber if it be not desired for any reason to plane it its full length. 110

The means here represented for shifting the clutch B³ consist of a rock-shaft, *b²*, having a downwardly-extending arm, *b³*, which engages the clutch B³, and an upwardly-extending arm, *b⁴*, from which a handle-rod or bar, *b⁵*, extends to the front of the machine. This bar *b⁵* has notches *b⁶*, any one of which may be engaged with a locking tooth, support, or projection, *b⁷*, as best shown in Fig. 2, and by means of this lock the clutch B³ may be held 115 out of engagement with both pinions B², or in positive engagement with either pinion. 120

It will be understood that inasmuch as the friction-pinion E' is clamped, as it were, between the two reversely-arranged friction-disks D D', motion will be imparted to the pinion E' and its shaft E, without any side strain upon the said pinion and shaft or upon the shaft-bearings, and therefore with little wear of the parts. 125

If it be desired at any time to instantly stop the feed, the disk D' may be relieved of the 130

action of the weighted lever D^2 , and, as here shown in Fig. 3, I have represented the lever D^2 as provided with an upwardly-extending handle d^8 , whereby it may be moved when desired in order to relieve the disk D' of the weight and move it slightly away from the disk D .

It will be obvious from the above description that the friction-disks and transmitting-shaft E , when combined according to my invention, are desirable whether the transmitting-shaft be employed to drive the feed-rolls through the usual pinion-shaft or through other mechanism.

I am aware that it is not new to drive the upright spindle of a wood-planing machine through a friction-wheel fixed on the spindle, and with which either of two concentric disks rotating in opposite directions may be brought into engagement to rotate the spindle in opposite directions.

What I claim as my invention, and desire to secure by Letters Patent, is—

1. The combination, with a transmitting-shaft through which feed-rolls are to be driven, of reversely-arranged friction-disks having a common axis, and a friction-pinion sliding on the transmitting-shaft radially to the axis of the disks toward and from said axis, substantially as herein described.

2. The combination, with a pinion-shaft from which the feed-rolls are to be driven, of reversely-arranged friction-disks having a common axis, a transmitting-shaft arranged transversely to the pinion-shaft and gearing therewith, and a friction-pinion sliding upon the transmitting-shaft radially to the axis of the disks toward and from said axis, and receiving motion by frictional engagement with the disks, substantially as herein described.

3. The combination, with a transmitting-shaft from which the feed-rolls are to be driven, of reversely-arranged friction-disks, one secured upon a driving-shaft and the other journaled independently of but concentric with the driving-shaft, bevel-gearing connecting the disks, whereby one is driven from but in a re-

verse direction to the other, and a friction-pinion in frictional engagement with and between said disks, and which is free to slide on the transmitting-shaft toward and from the center of said disks, substantially as herein described.

4. The combination, with a pinion-shaft from which the feed-rolls are to be driven, and which has a bevel-wheel upon its end, of reversely-arranged friction-disks having a common axis, a transmitting-shaft arranged transversely to the pinion-shaft and between the disks, reversely-arranged bevel-pinions and a clutch on the transmitting-shaft, whereby it may be connected to drive the pinion-shaft in reverse directions, and a friction-pinion in frictional engagement with and between said disks, and which is free to slide on the transmitting-shaft toward and from the center of said disks, substantially as herein described.

5. The combination, with the pinion-shaft B , and the transmitting-shaft geared therewith, of the driving-shaft C , the disks $D D'$, the former secured to the driving-shaft and the latter having its axis concentric therewith, the friction-pinion E' , fitted to slide on the shaft E and between the disks, a hand-lever for moving said pinion, and a weighted lever for pressing the disk D' toward the disk D , substantially as herein described.

6. The combination, with the pinion-shaft B , and the transmitting-shaft E , geared therewith, of the driving-shaft C , the friction-disks $D D'$, geared together to rotate in reverse directions, and the former secured upon the driving-shaft, the friction-pinion E' , fitted to slide on the shaft E and between the disks, and hand-levers whereby the pinion E' may be slid along the shaft E to vary the speed transmitted to the pinion-shaft B , and whereby the disk D' may be moved away from the other disk, substantially as herein described.
